UNITED STATES PATENT OFFICE.

JOSEPH MILLER, OF NEW YORK, N. Y.

DESIGN FOR A LIGHTING-FIXTURE TASSEL.

Application filed October 25, 1923. Serial No. 7,597. Term of patent 3½ years.

To all whom it may concern:

Be it known that I, JOSEPH MILLER, a citizen of the United States, and a resident of the city of New York, borough of Manhattan, in the county and State of New York, have invented a new, original, and ornamental Design for a Lighting-Fixture Tassel, of which the following is a specification, reference being had to the accompanying drawings, forming part thereof.

The figure is a perspective view of a tassel embodying my design.

I claim:

The ornamental design for a lighting-fixture tassel, as shown.

JOSEPH MILLER.
